United States Patent Office.

FRANKLIN SHAW, OF BRAINTREE, MASSACHUSETTS.

Design No. 2,660, dated May 28, 1867.

DESIGN FOR A HEEL-PLATE FOR BOOTS, &c.

The Schedule referred to in these Letters Patent and making part of the same.

TO ALL WHOM IT MAY CONCERN:

Be it known that I, FRANKLIN SHAW, of Braintree, in the county of Norfolk, and State of Massachusetts, have invented and designed a new form of heel-plate for boots and shoes, which I term the "Excelsior" Heel-Plate; and of which the following is a full, clear, and exact description, reference being had to the accompanying drawings, making a part of this specification.

Figure 1 is an under side view of the heel-plate as applied to the heel of a boot or shoe.

Figure 2 is an edge or side view.

A represents the heel-plate; B the boot or shoe heel, I form the heel-plate A of sheet metal, cut by a die, into the peculiar outline form indicated in fig. 1, and attached to the heel by nails or screws. The outline of the heel-plate is composed of three convex curved lines, the curved line a conforming to the rear part of the heel, and terminating at the points b b, and the two similar gibbous curves c c commencing at said points b b and retiring to a point of junction at d.

Claim.

I claim the design of the "Excelsior" heel-plate of the outline form represented, substantially as set forth.
